UNITED STATES PATENT OFFICE.

WILLIAM EDWARD RAHMER, OF GARRETT, INDIANA.

MEANS FOR SPREADING AND DISTRIBUTING BALLAST.

1,321,771.

Specification of Letters Patent.

Patented Nov. 11, 1919.

Application filed May 6, 1919. Serial No. 295,053.

To all whom it may concern:

Be it known that I, WILLIAM E. RAHMER, a citizen of the United States, residing at Garrett, in the county of Dekalb and State 5 of Indiana, have invented new and useful Improvements in Means for Spreading and Distributing Ballast, of which the following is a specification.

This invention comprehends the provision 10 of a device for spreading and distributing the ballast over the roadbed between and on opposite sides of the rails of a track.

In carrying out the invention I provide a device for the above purpose, designed to fit 15 over the rails of the track for sliding movement thereon, the device including among other features a plate terminating close to the roadbed so as to spread and distribute the ballast, when the device is being used.

Another object of this invention resides 20 in the provision of a device of this kind, which can be readily and easily associated with the end of a freight car or other rolling stock, utilized for moving the device along 25 the track.

The nature and advantages of the invention will be better understood when the following detailed description is read in connection with the accompanying drawing, the 30 invention residing in the construction, combination and arrangement of parts as claimed.

In the drawings forming part of this specification, the like numerals of reference 35 indicate similar parts in the several views, and wherein:—

Figure 1 is a perspective view of the roadbed, a car being shown in end elevation, and the device associated therewith showing the 40 manner of using the same.

Fig. 2 is a similar view with the ballast removed from a part of the roadbed, showing more clearly the manner of associating the device with the car and the rails of the 45 track.

Fig. 3 is a vertical sectional view taken through the device as shown in Fig. 1.

Fig. 4 is a sectional view taken on lines 4-4 of Fig. 2.

Fig. 5 is a perspective view of the track 50 engaging member in its entirety.

Fig. 6 is a rear elevation of the same.

The device constructed in accordance with my invention essentially embodies an elongated rectangular plate 10 constructed from metal or other suitable material, and adapt-

ed to be arranged edgewise across the rails A of the track. The plate 10 can be made of any suitable dimension, but it is preferably of a length to extend beyond both rails A a 60 sufficient distance to terminate beyond the ends of the ties B. The lower longitudinal edge of the plate 10 is provided at proper points in the length of the plate, with rail receiving notches 11 which permit the plate 65 to be lowered between and on both sides of the rails to a position in close proximity to the roadbed, for the purpose to be presently set forth. It is to be understood that the plate 10 is adapted to be moved along the 70 track for the purpose of spreading and distributing the ballast between the rails and on the opposite sides thereof. The notches 11 are small at the top to nicely accommodate the heads of the rails, but are relatively 75 wide at the bottom to facilitate the association of the device with the rails of the track or its removal therefrom as the occasion may require. The notches 11 further prevent any lateral displacement of the device with 80 respect to the roadbed while the device is being used.

Any suitable means may be employed for connecting the plate 10 with the end of a freight car or other rolling stock indicated 85 at C, the latter being utilized for moving the plate along the track for the purpose mentioned. However, as shown in this specific instance, the plate 10 is riveted or otherwise suitably secured to the track engaging element 12 which may be an ordinary 90 wooden log of a length equal to the length of the plate 10 in order to bridge the space between the rails B and rest thereon. Metallic wear plates 13 are suitably secured to 95 the underside or bottom of the element 12 and are interposed between the latter and the rails of the track. The plates 13 are each provided with an angularly disposed portion 14 which is vertically disposed at 100 the rear of the element 12 projecting an appreciable distance above the top thereof. Both the bottom and rear side of the element 12 is recessed as at 15 to receive the shoes 13 whereby the latter lie flush with the adjacent surfaces of the element 12. The upright portions 14 of the shoes are disposed immediately in advance of the wheels of the car C and are adapted to be engaged thereby so that when the car is put in motion the 110 wheels will revolve against the shoes and slide the device in its entirety along the

track. The shoes are grooved to receive the flanges of the wheel, and in which grooves the wheels rotate. Arranged in superimposed relation upon the element 12 is the desired number of logs or beams 17 to place the weight of the car upon the element 12, a number of wedges 18 being driven between the uppermost log 17 and the adjacent part of the car C to hold the component parts 10 of the device fixed relatively with respect to each other and the car C.

In practice, when it is found necessary to spread and distribute the ballast over the roadbed of a railroad track, the plate 10, 15 element 12 and shoes 13 is associated with the rails of the track as a unit in the manner above described, all of said parts being securely fastened together. Subsequent to the positioning of these parts upon the rails of 20 the track the logs or timbers 17 are arranged one by one in superimposed relation upon the element 12 until a wall of the proper height is built. The wedges 18 are then effectively driven between the uppermost log 25 and suitable parts of the car C to give the wall thus built the proper strength and rigidity so as to be conveniently moved along the track by means of the car C. The construction is such that the component parts of 30 the device may be quickly and easily assembled or disassembled as the occasion may require.

While I have shown and described the preferred embodiment of the invention, I 35 desire to have it understood that the same is merely illustrative and that I do not limit myself to the exact construction and arrangement of parts disclosed, as such changes may be resorted to when desired as 40 fall within the scope of what is claimed.

What I claim is:—

1. A device for spreading and distributing the ballasts over the bed of a railroad, including a member adapted to extend across

the rails of the track and having portions 45 disposed below the heads of the rails at both sides thereof, a plurality of beams arranged in superposed relation and defining with said member a wall adapted to support the weight of one end from the car and wedges 50 driven between the uppermost beam in the adjacent part of the car for holding the said beam and wall fixed relatively with respect to the end of the car whereby the wall is moved over the track with said car. 55

2. A device of the class described comprising a member adapted to extend across the rails of a track and having rail receiving notches whereby said member extends below the heads of the rails at both sides thereof. 60 means for holding said member fixed relatively with respect to the car, whereby the member is moved along the track with the car, shoes secured to said member and including vertically disposed portions arranged in advance of the wheels of the car, and said vertically disposed portions having grooves in which the wheels rotate. 65

3. A device for spreading and distributing ballasts over the bed of a railroad, including 70 a member adapted to extend across the rails of the track and having portions disposed below the heads of the rails at both sides thereof, a plurality of beams arranged in superimposed relation and defining with 75 said member a wall adapted to support the weight of one end of the car, wedges driven between the uppermost beam and the adjacent part of the car for holding the wall fixed relatively with respect to the car 80 whereby the wall is moved over the track with the car, metallic shoes secured to the bottom of said wall for engagement with said rails, and said shoes including vertically disposed portions having grooves in 85 which the wheels of the car rotate.

In testimony whereof I affix my signature.

WILLIAM EDWARD RAHMER.
